PAPER MACHINE

Filed July 9, 1928

UNITED STATES PATENT OFFICE.

ROBERT EDWARD ARGY, OF NIAGARA FALLS, NEW YORK.

PAPER MACHINE.

Application filed July 9, 1928. Serial No. 291,274.

This invention relates to a paper machine. The object of the invention is to provide a paper machine in which novel provision is made for pre-heating the paper web prior to its passage through the wet pressing apparatus of the machine to the end that the paper web may be thus pre-heated with minimum attending alteration in and departure from the construction and arrangement of existing paper machines.

With this object in view and such others as may hereinafter appear, the invention consists in the paper making machine and in the combinations, structures and arrangements of parts hereinafter described and particularly defined in the claims at the end of this specification.

In the drawing I have illustrated a sufficient portion of a paper making machine to enable the features of the present invention to be understood.

The present invention aims to provide a novel and improved construction of paper making machine in which novel provision is made for pre-heating the paper web prior to the time that it has completed its passage through the wet pressing apparatus of the machine and the construction of which is such as to enable existing paper machines to be modified or altered to produce the improved machine in a simple, inexpensive manner. To this end the invention contemplates the provision of a combined paper guiding and heating roll adjacent a pair of the press rolls of the wet pressing apparatus and around which the paper web is passed to be pre-heated and guided between said press rolls. In the preferred form of the invention a pair of combined paper guiding and pre-heating rolls are substituted for the usual paper carrying rolls located between the last wet press rolls and the usual set of driers at the end of the paper machine, so that in adapting an existing paper machine to one embodying the features of the present invention it is only necessary to substitute such steam-heated pre-heating and guiding rolls for the usual paper carrying rolls.

Referring now to the drawing, 10 represents the paper web after it has been formed and as it is being conducted through the wet pressing apparatus, herein shown as comprising one set of wet press rolls 12, 13, and a second or last set of press rolls 14,

15. The paper is conducted through the first wet press rolls while supported upon the usual felt indicated at 18.

Prior to the passage of the web of paper through the last set of wet press rolls 14, 15, provision is made for conducting the paper around steam heated rolls 20, 22, which are preferably of the size and are located at the usual places in the machine occupied by the usual paper carrying rolls and which serve in the improved paper machine as combined pre-heating and guiding rolls for conducting the paper web to a correct position to permit it to pass between the last set of press rolls 14, 15. As herein shown, the combined paper guiding and pre-heating rolls comprise hollow steel rolls connected by supply pipes 26, 27 to a header 28 supplied with steam from any suitable source of supply (not shown), and the flow of steam to each roll is controlled in any suitable manner as by valves 30, 31. As stated, in the operation of the machine the paper web is conducted around the lower paper guiding and pre-heating roll 20, thence around the upper of such rolls 22 and between the last set of wet press rolls 14, 15. After having passed between the wet press rolls 14, 15, the paper web is conducted around the usual guide roll 34 and thence to the usual set of driers 40 at the end of the machine, passing over a baby drier 42 as shown.

From the description thus far it will be observed that an existing paper machine may be readily and economically modified to be capable of pre-heating the paper web prior to the time that it completes its passage through the wet presses of the paper machine. It has been found that the pre-heating of the paper web in this manner facilitates the mechanical extraction of the water from the web so that the wet presses are enabled to extract much more water than has heretofore been possible with paper machines in which no pre-heating has been practiced. This result is undoubtedly due to the decrease in the surface tension of the water included within the web. As a result of the pre-heating, economies in steam consumption in the final driers may be obtained, enabling paper to be produced more economically and rendering possible the operation of the machine at increased speeds

as compared with existing prior paper machines employing no apparatus for pre-heating of the paper web.

It is to be understood that while it is preferred to heat the combined pre-heating and guiding rolls with steam, nevertheless other means of heating may be used if desired.

While the preferred embodiment of the invention has been herein illustrated and 10 described, it will be understood that the invention may be embodied in other forms within the scope of the following claims.

Having thus described the invention what is claimed is:

- 15 1. In a paper making machine, the combination with the last wet press rolls of an upper and lower paper carrying roll positioned between the last press rolls and the final driers, and means for heating one of 20 said paper carrying rolls to pre-heat the paper web prior to its passage through the last wet press rolls.
2. In a paper making machine, the combination with the last web press rolls of an 25 upper and lower paper carrying roll positioned between the last press rolls and the final driers, and means for heating both of

said paper carrying rolls to pre-heat the paper web prior to its passage through the last wet press rolls.

3. In a paper making machine, the combination with the usual set of driers and the last wet press rolls of combined paper guiding and pre-heating rolls interposed between the driers and the last wet press rolls and 35 around which the web is led prior to its passage through the last wet press rolls.

4. In a paper making machine, in combination, a pair of wet press rolls, and a combined heating and guiding roll positioned 40 adjacent the said wet press rolls and around which the paper is passed to be heated and to be guided between said wet press rolls.

5. In a paper making machine, in combination, a pair of wet press rolls, a pair of 45 paper carrying rolls adjacent said press rolls and around which the paper is conducted to be guided between said press rolls, and means for heating one of said guide rolls to pre-heat the paper web just prior to its passage between said press rolls.

In testimony whereof I have signed my name to this specification.

ROBERT EDWARD ARGY.
